(57) **CLAIM**

We claim the ornamental design for a storage handle for a camera, as shown and described.

DESCRIPTION

FIG. 1 is an exploded perspective view of the storage handle for a camera showing our new design, wherein the end cap is shown removed to allow access to the storage tube; the dashed line showing of a camera mounted on the storage handle is for illustrative purpose only and does not form a part of the invention;

FIG. 2 is a perspective view of the storage handle with the end cap attached to the storage tube;

FIG. 3 is a right-side elevational view thereof; the left side elevational view being a mirror image thereof;

FIG. 4 is a front elevational view thereof;

FIG. 5 is a rear elevational view thereof;

FIG. 6 is a bottom plan view thereof; and,

FIG. 7 is a top plan view thereof.
